UNITED STATES PATENT OFFICE

158,001

TEAKETTLE

Fred D. Patti, Chicago, Ill., assignor to Steelco
Stainless Steel, Inc., Chicago, Ill., a corporation of Illinois

Application February 19, 1947, Serial No. 137,015

Term of patent 14 years

(Cl. D44—25)

To all whom it may concern:

Be it known that I, Fred D. Patti, a citizen of the United States and a resident of Chicago, in the county of Cook and State of Illinois, have invented a new, original, and ornamental Design for a Teakettle, of which the following is a specification, reference being had to the accompanying drawing, forming a part thereof.

Fig. 1 is an elevational view of a teakettle, showing my new design.

Fig. 2 is a plan view of the same.

The dominant features of the design reside in the handle and base therefor, as shown.

I claim:

The ornamental design for a teakettle, substantially as shown and described.

FRED D. PATTI.
